(57) **CLAIM**

The ornamental design for an eyeglass temple bending device, as shown and described.

DESCRIPTION

FIG. 1 is a top perspective view of an eyeglass temple bending device showing my new design;

FIG. 2 is a front end view of the eyeglass temple bending device of FIG. 1;

FIG. 3 is a right side elevation view of the eyeglass temple bending device of FIG. 1;

FIG. 4 is a left side elevation view of the eyeglass temple bending device of FIG. 1;

FIG. 5 is a rear end view of the eyeglass temple bending device of FIG. 1;

FIG. 6 is a top plan view of the eyeglass temple bending device of FIG. 1; and,

FIG. 7 is a bottom plan view of the eyeglass temple bending device of FIG. 1.

The broken lines depict environmental subject matter only and form no part of the claim.

The stipple shading and shade lines in the Figures show contour and not surface ornamentation.
